United States Patent Office.

CARL MILLAR, OF SANDOVAL, ILLINOIS.

Letters Patent No. 79,077, dated June 28, 1868.

IMPROVED SMUT-MACHINE.

The Schedule referred to in these Letters Patent and making part of the same.

TO ALL WHOM IT MAY CONCERN:

Be it known that I, CARL MILLAR, of Sandoval, in the county of Marion, and State of Illinois, have invented a new and improved Smut-Machine; and I do hereby declare that the following is a full, clear, and exact description thereof, which will enable others skilled in the art to make and use the same, reference being had to the accompanying drawings forming part of this specification.

The nature of my invention relates to improvements in apparatus for smutting and cleaning grain, the object of which is to provide a machine that will do the work in a more satisfactory manner than any now in use, without additional cost.

It consists in providing on a suitable framing a vibrating-screen, to which the grain is first fed to remove the straw and coarse material, from which the grain is delivered to a vertical conical smutter, made of an outer shell and interior drum of perforated sheet metal, and provided at its base with a fan, through which the grain is passed to a vertical conically-shaped brushing-apparatus, also provided with a fan at its base, through which the grain is also passed to another vibrating-screen, and from thence to the hopper for grinding, as will be more fully described on reference to the accompanying drawings, wherein—

Figure 1 represents a front elevation of my improved machine, and

Figure 2 a central vertical section of the same.

Similar letters of reference indicate corresponding parts.

A represents the framing, and B a vibrating-screen, to which the grain is delivered from the spout B', and which receives vibrating motion from the oscillating-shaft a , connecting-rods a^1 and a^2 , rock-shaft a^3 , and tappets on the shaft a^4 of the brushing-apparatus. From the screen B, the grain passes to the smutter C, which is composed of a conically-shaped perforated sheet-metal casing, within which is provided a conical perforated sheet-metal core, arranged upon a vertical shaft, to which a high velocity is communicated by a belt on the pulley D. After passing through the above-described smutter C, the action of which on the grain is well understood, and which does not need further description, it passes into a fan-blower, E, which separates the particles of smut and other foul matter from the grain in passing the smutter, by blowing it out through the spout F, and conveys the grain to a spout communicating from the spout F to the brushing and scouring-apparatus G, also arranged in a vertical position, and composed of a hollow conical outer shell, provided on its interior surface with brushes, and an interior rotating conically-formed core, also provided on its outer surface with brushes, the lines of brushes on the shell and core being arranged at different angles with one another, so that they pass each other in the manner of the edges of a pair of shears, whereby a steady and uniform action is maintained. From the brushing-apparatus G, the grain passes to another fan-blower, which separates the remaining refuse matter, by blowing it off through the spout F, and which delivers the grain to another vibrating-screen K, shown in dotted lines in fig. 2, and which receives motion from the oscillating-shaft S, connecting-rod b^2 , oscillating-shaft b^3 , arm b^4 , and tappets b^5 , on the smutter-shaft b^6 . From the screen K the grain is delivered through the spout L.

The shafts b^6 and a^4 of the smutter and brusher have their lower bearings in the cross-beams M M, which are suspended at one end from the screw-rod N, whereby they may be lowered or raised, to adjust the cores of the smutter and brusher, so that the spaces between them and their outer shells may be graduated to the various sizes of grain for which they may from time to time require to be used. Motion is communicated to the brusher from the shaft of the smutter by a belt, o. The screen K may be provided with sieves of different degrees of meshes, for separating the small grains from the large if desired, and with different spouts, L' and L'', to convey the separated kinds away.

I claim as new, and desire to secure by Letters Patent—

The smut-machine C, with its screen B and blower E, in combination with the brusher G, blower H, and screen K, when constructed and arranged in the manner and to operate substantially as described.

CARL MILLAR.
